UNITED STATES PATENT OFFICE

146,351

DESIGN FOR A BOTTLE

John L. Dunnock, Baltimore, Md., assignor to
Swindell Brothers, Incorporated, Baltimore,
Md.

Application September 24, 1945, Serial No. 122,319

Term of patent 7 years

(Cl. D58—8)

To all whom it may concern:

Be it known that I, John L. Dunnock, a citizen of the United States, residing at Baltimore and State of Maryland, have invented a new, original, and ornamental Design for a Bottle, of which the following is a specification, reference being had to the accompanying drawing, forming part thereof.

Figure 1 is a front elevational view of a bottle, showing my new design,

Figure 2 is a side elevational view thereof, and
Figure 3 is a plan view thereof.

I claim:

The ornamental design for a bottle, substantially as shown.

JOHN L. DUNNOCK.
